CONCRETE BLOCK HANDLING TOOL

Louis F. Looze, Buffalo, N. Y.

Application October 23, 1950, Serial No. 191,522

3 Claims. (Cl. 72—129)

1

This invention relates to certain new and useful improvements in tools or implements for facilitating the handling and laying of concrete and like building blocks.

One of its objects is to provide a tool of this character which is so designed and constructed as to facilitate the laying of the blocks in properly spaced and aligned relation both vertically and horizontally of the building wall.

Another object of the invention is to provide a block handling tool which is self-adjustable to accommodate the handling of blocks of different widths and which is so constructed as to be readily adaptable to the handling of half-blocks.

Other features of the invention reside in the construction and arrangement of parts herein-after described and particularly pointed out in the appended claims.

In the accompanying drawings:

Figure 1 is a perspective view of the tool embodying my invention. Figure 2 is an enlarged end view thereof, partly in section. Figure 3 is a top plan view of the tool. Figure 4 is a fragmentary side view of the tool, partly in section, showing the releasable means for governing the vertical spacing between the blocks. Figure 5 is a fragmentary vertical section taken on line 5—5, Figure 4. Figure 6 is a fragmentary cross section taken substantially on line 6—6, Figure 2. Figure 7 is an end view of the tool in gripping engagement with a block of less width than that depicted in Figure 2.

Similar characters of reference indicate corresponding parts throughout the several views.

In the preferred embodiment of the invention shown in the drawings, the tool consists of a laterally-expansible frame to releasably receive and grip a building block of concrete, cinder or similar composition, such frame being of open rectangular design composed of laterally-spaced, substantially upright front and rear end bars or legs 10, 11 which are adapted to embrace the upper half of a building block and from the upper ends of which extend opposing inclined suspension arms 12 pivoted intermediate their ends to each other at 13 and to the ends of a longitudinal handle bar 14 spanning such end bars. Beyond their pivots these suspension arms are pivotally connected by links 15 to the ends of a second handle bar 16 companion and parallel to the handle bar 14, so that by grasping the handle bars with one hand and drawing them together the frame is caused to expand to an open position, shown by dotted lines in Figure 2, to receive a block for laying or release a block after

2

laying. Substantially at the junction of the cross arms 12 with their companion pendant side bars 10, 11 and yieldingly connecting the same are transversely-disposed springs 17 which normally serve to urge and retain the frame in its contracted position for clamping engagement with the block during handling. The handle bars 14, 16 may be covered with a rubber tubing or the like for gripping purposes.

Joined to the lower opposite ends of the block-embracing frame-arms 10, 11 and pivoted intermediate their upper and lower ends at 18 for swiveling-like movement transversely relatively thereto are upright block-engaging members 19 having springs 20 coiled about the pivots thereof with one end of each spring bearing against the adjoining frame-arm and the opposing end thereof bearing against the companion block-engaging member for yieldingly urging it flatwise against the face of the block being handled, as shown in Figures 2 and 7, wherein the tool is depicted with blocks of different widths. Rigidly secured to the outer faces of these block-engaging members adjacent the upper and lower ends thereof are companion upper and lower longitudinal side or tie bars 21 and 22, respectively, the upper bars 21 extending forwardly beyond the companion block-engaging members 19 at one end of the tool to provide tongues or extensions 23 which are adapted to abut laterally against the opposite sides of the opposing end of an adjoining laid block as the tool carrying the block about to be laid is brought into endwise relation to such previously laid block, to thereby assure proper longitudinal alinement of the blocks as they are laid endwise one against the other. To properly position a block in its endwise relation to the tool and to provide a mortar space between such block and the end of an adjoining laid one, the front or companion ends of the lower side bars 22 extend beyond the adjoining upright members 19 and terminate in inwardly directed or lateral block-engaging lugs 24 which are adapted to abut at their outerfaces against the opposing end of a laid block as the block borne by the tool and about to be laid is brought into an operative block-laying position. It will be noted that the lower ends 25 of the pivoted block-engaging members 19, when the tool is in the block-laying position shown by full lines in Figure 2, extend below the mortar space between superposed blocks and overlie the upper opposite side faces of the subjacent block to provide lateral bearing gages which function to aline the blocks vertically as they are laid.

For the purpose of releasably effecting a proper vertical mortar spacing of the blocks in a true horizontal position, the tool-frame is provided with displaceable gaging elements 26 which serve to properly support the frame-carried block about to be laid and, after being laid, are adapted to be displaced to a position to readily effect the release of the tool from the weight of the block so as to thereafter enable the tool to be freely expanded and removed from operative engagement with the laid block. One of these displaceable elements 26 is provided adjacent the lower end of each pivoted block-engaging member 19 below the lower frame-bars 22 and each faces inwardly and is attached to a trunnion 27 free to revolve about a horizontal axis in said companion member and having a crank arm 28 fixed on its outer end. The crank arms at each side of the frame are pivotally connected by links 29 to the opposite ends of a swiveling and axially-shiftable actuating handle 30 pivoted at 31 centrally of the companion lower frame-bar 22. Secured to the latter about the pivot 31 is a segmental-shaped plate 32 having spaced ears 33 projecting outwardly from its upper edge and between which the actuating handle is centrally retained in an upright position when the displaceable elements 26 are in their vertical or normal block-supporting position, shown in Figures 1, 2 and 4. A spring 34 connected at one end to the handle-pivot and at its other end to the handle serves to yieldingly urge the latter laterally inward into latched relation between the plate-ears 33, while springs 35 connected at one end to the companion links 28 and at their other ends to the adjoining frame-bar 22 serve to urge the companion cranks 28 and their displaceable elements 26 to their normal block-sustaining position, shown by full lines in Figure 4, with the operating handle 30 in its upright latched position. In the released position of the displaceable elements 26, shown by dot-dash lines in the same figure, the operating handle assumes a horizontal position and it is frictionally retained in such position between the outer face of segmental plate 32 and a yieldable lug 36 formed on such plate. As shown in Figure 4, the angularly displaceable elements 26 are of substantially flat, rectangular or web-like shape, so that when they are displaced to a released position, they are clear of edgewise contact with the opposing faces of the superposed blocks, and when the frame is expanded these elements will freely disengage from between the blocks.

This tool is also designed to facilitate the laying of half or shorter than full length blocks and for this purpose I provide means substantially centrally of the frame for supporting such smaller sized block to supplement the front displaceable elements 26. For this purpose, each segmental plate 32 has an inwardly extending fixed lug 37 centrally of its lower edge which, as shown in Figures 3 and 5, projects sufficiently inwardly from the adjoining lower frame bar 22 to form a supporting ledge for the outer end portion of the block being handled.

I claim as my invention:

1. A tool of the character described, comprising a substantially rectangular, laterally-expansible frame including laterally-spaced pendant bars at its front and rear ends, companion front and rear block-engaging members fulcrumed intermediate their upper and lower ends to said companion frame-bars in pendant, transverse swiveling rela-

tion thereto, means in operative relation to said members for yieldingly urging them toward bearing contact with the block being handled, said block-engaging members having extensions at their lower ends for facial alining contact with the opposite sides of an adjoining subjacent laid block and the front members having forwardly-facing extensions at their upper ends for facial alining contact with the opposite sides of an endwise-aligned block, and angularly-displaceable block-supporting and gaging elements rotatably mounted on the lower ends of said members.

2. A tool for handling building blocks, comprising a substantially rectangular, laterally-expansible frame including laterally-spaced pendant bars at its front and rear ends with handle bars for governing the expanding movements of the frame and yieldable means for normally urging said frame to a contracted position, block-gripping members fulcrumed intermediate their upper and lower ends to said frame-bars to swing laterally thereof and having springs coiled about the fulcrums thereof and bearing at one end against said members for urging them into facial contact with a block, said members having portions above and below their fulcrums for alining a block borne by the tool with adjoining laid blocks, angularly-displaceable block-supporting and gaging elements rotatably mounted adjacent the lower ends of said members, and means operatively connected to said elements for actuating them to and from a block-releasing position.

3. A tool for handling building blocks, comprising a substantially rectangular, laterally-expansible frame including laterally-spaced pendant bars at its front and rear ends with handle bars for governing its expanding movements and yieldable means for normally urging it to a contracted position, block-gripping members pendantly hung from said frame-bars to swing laterally thereof and having springs connected thereto for urging them into facial contact with a block, upper and lower longitudinal tie bars connecting the front and rear pendant members at each side of the frame, the upper tie bars having forwardly-facing extensions at one end for facial alining contact with the opposite sides of an endwise-aligned block and the lower tie bars having inwardly directed lugs thereon for abutting contact with the end of an adjoining laid block, angularly-displaceable block-supporting and gaging elements mounted on the lower ends of said block-engaging members, and actuating handles fulcrumed substantially centrally on the lower tie bars and operatively connected to the companion displaceable elements for actuating them to and from a block-releasing position.

LOUIS F. LOOZE.
